UNITED STATES PATENT OFFICE.

THEODORE W. HANRATH, OF CHICAGO, ILLINOIS, ASSIGNOR OF ONE-HALF TO JOSEPH H. GOLDNER, OF CHICAGO, ILLINOIS.

MOP-WRINGER.

1,257,224.

Specification of Letters Patent. Patented Feb. 19, 1918.

Application filed February 5, 1917. Serial No. 146,647.

To all whom it may concern:

Be it known that I, THEODORE W. HANRATH, a citizen of the United States, and a resident of Chicago, in the county of Cook and State of Illinois, have invented certain new and useful Improvements in Mop-Wringers; and I do hereby declare that the following is a full, clear, and exact description thereof, reference being had to the accompanying drawings, and to the letters of reference marked thereon, which form a part of this specification.

This invention relates to improvements in mop wringers, and consists of the matters hereinafter described and more particularly pointed out in the appended claims.

The improved mop wringer is of the kind in which the pressure applied for squeezing the water from the mop cloth or fabric may be applied by the foot, thus obviating the necessity of stooping or bending the body when operating the device.

The object of the invention is to produce a device of the kind described, which is efficiently and easily operated; which is cheap to manufacture; which in its preferred form provides a movable support for clean water and the dirty water wrung from the mop cloth; and which is collapsible so that it requires but little space when put away in the interims of its use.

The objects and advantages of the invention will more fully appear as I proceed with the specification.

35 In the drawings:

Figure 1 is a view presenting a side elevation of a mop wringer made in accordance with the invention.

40 Fig. 2 is a top plan view of the same.

Fig. 3 is a view presenting a longitudinal, vertical section through the mop wringer in a plane indicated by the line 3—3 of Fig. 2.

Fig. 4 is a view presenting a rear elevation of the improved mop wringer.

45 Referring now to that embodiment of the invention illustrated in the accompanying drawings:—5 indicates the base of the device. Said base consists of a platform 5^a, preferably made of wood, provided at or near its four corners with supporting caster wheels 6, upon which it may be easily moved from place to place. The base is longer than it is wide, and parallel angle bars 7, 7 are attached to its top along its longer edges 55 with one flange vertical and flush with said

edges. 7^a, 7^a indicate strap irons fixed to the ends of the base and connected to the angle bars 7, 7 for strengthening the base.

The platform 5^a, as shown, is made large enough to support two buckets, one for clean water and one to receive the water wrung from the mop cloth. The wringer mechanism is placed above the part of the platform, that is to be occupied by the last named bucket, and is supported thereon by a collapsible frame, 8^a.

The collapsible frame 8^a comprises four upright, flat, metal bars 8, 8, 9, 9, pivotally connected to the angle bars 7, 7 of the base; a pair of parallel angle bars 10, extending lengthwise of the base and each connecting, by pivotal pins, an upright 8 and an upright 9; parallel, spaced angle bars 11, 11 extending crosswise of the base and rigidly connecting the bars 10, 10 at or near their ends; and a pair of diagonal brace bars 14, each pivotally connected at its ends to an upright 8 and to an upright 9, one of said ends, (the end 14^a as illustrated) being detachably connected to its pivot pin 9^a in a familiar manner. The diagonal bars 14 act to hold the side members of the frame 8^a from collapsing.

The bars 10, 10 and 11, 11 form an open frame on which is carried a perforated plate 13. Said plate constitutes the stationary member of the wringing device against which the mop cloth is pressed or squeezed and through the perforations of which, the water pressed from the cloth, drains or drips into a bucket placed below it on the platform 5^a. The plate 13, as shown, is attached at its sides to bars 12, 12 (see Fig. 2) which in turn are attached to the cross bars 11 of the frame.

95 The movable member of the wringer consists of a jaw, which, as shown herein, is hinged to the frame and is actuated by a foot lever to engage a mop head with the mop cloth attached. Said jaw consists of 100 a flat bar 18^a extending crosswise of the frame and of two parallel, spaced angle bars 18, 18 extending at right angles to said bar 18^a and each rigidly attached to it at one end. The other ends of said angle bars are 105 pivotally mounted on a cross-rod 17 carried by upright bars 16, 16 which are fixed to the angle bars 12, 12 at the sides of the perforated plate 13. 19 indicates a cross-rod extending through and engaged in suitable 110

holes in the bars 18 near their ends and above the jaw bar 18^a. Said rod 19 extends beyond the sides of the perforated plate 13 and is operatively connected at its ends by 5 flat link bars 24, 24 to the side arms 21^a, 21^a of a U-shaped foot lever or treadle 20. The lever arms 21^a, 21^a, are located outside the upright members of the collapsible frame and are fulcrumed on a horizontal 10 cross-rod 22 mounted on the uprights 8, 8 and projecting beyond the outer faces of said bars. The jaw bar 18^a is normally held in raised position by means of spring controlled levers 25, 25 fulcrumed on the rod 17 15 to which the said jaw bar is hinged. Said levers engage at one end under the cross rod 19 and at the other end are connected by coiled springs 26 to the cross-rod 22.

The operation of the mop wringer is as 20 follows:—With the wringer arranged in its “set up” position, pails or buckets 27, 28 indicated in dotted lines in Fig. 1, are placed on the platform 5^a. The pail 27 containing clean water is placed on the front end of 25 said platform and an empty pail 28 is placed on the rear end of the platform beneath the perforated plate 13. The mop head 29, indicated in dotted lines in Fig. 3 (and which forms the subject matter of a separate application for patent, filed by ourselves on even date herewith, and bearing Serial Number 30 146,648) is brought to bear upon the perforated plate 13,—the operator still retaining his hold on the handle. The transverse 35 member of the U-shaped lever or treadle, indicated at 21^b, is now engaged and depressed by the foot. The depression of the lever 20 actuates the links 24 to pull down on the rod 19, which swings the jaw-bar 18^a 40 down upon the mop head and forcibly presses it against the perforated plate. The mop cloth on the head is thus squeezed between the bottom of the mop head and the perforated plate 13, and the water is wrung 45 out of it and drained through the perforations of the plate 13 into the bucket or pail 28 below it.

As will be understood, the downward movement of the treadle and of the jaw-bar 50 18^a has been resisted by the spring controlled bars 25. Thus, when the foot is removed from the treadle or foot lever, said treadle, with the jaw-bar, will be returned to its first position. The upward movement 55 of the parts is limited by the side bars 21^a of the treadle striking the pivot pins connecting the uprights 9 of the collapsible frame with the top bars 10 thereof, (see Figs. 1 and 2) which are projected for that 60 purpose.

After the mop cloth has been wrung out and when it is being used for washing purposes, it is again dipped into the clean water in the pail or bucket 27, and the mopping process is carried on in the usual way.

The structure described may be easily moved from place to place on the floor which is being mopped, and provides support for both the clean washing water and for the dirty water wrung from the mop. This is 70 of great convenience, as will be readily understood, since, even when drying a floor, it is possible to wash the mop cloth in the clean water carried by the bucket 27 and then wring the mop cloth dry before applying it to the floor after it has been washed. 75

By detaching the ends 14^a of the diagonal bars 14 from their respective pivot pins 9^a, the collapsible frame may be swung on the bottom pivotal ends of its uprights 8, 9, 80 from the position shown in full lines in Fig. 1 to the position shown in dotted lines. This, of course, is done after the buckets or pails have been removed from the platform 5^a and puts the apparatus into more convenient shape for disposal in a closet or other place out of sight. The collapse shown is easily brought about by reason of the construction heretofore described.

That the improved wringer may be easily 90 and cheaply manufactured is manifest from the construction of parts described. All of said parts may be made from bar, strap and angle iron which may be bought at any time on the open market and which only requires 95 to be cut to the required dimensions. The remaining assembling and riveting required, demands no expert labor.

While in describing my invention, I have referred to certain details of mechanical 100 construction and arrangement of parts, it is to be understood that the invention is in no way to be limited thereby except as may be pointed out in the appended claims.

I claim as my invention:

1. A mop wringer comprising a base, upright, spaced bars arranged in pairs, pivoted at their bottom ends to the lateral edges of said base, a frame pivoted to the top ends of said spaced bars, a perforated plate carried 110 by said frame, a movable jaw capable of a vertical movement carried by said frame above said perforated plate, a treadle pivoted to one pair of said bars, means operatively connecting said treadle with said movable jaw for imparting a downward movement to said movable jaw toward said plate when said treadle is depressed, and means for returning said movable jaw and treadle to their normal position upon release 115 of said treadle.

2. A mop wringer comprising a base, upright, spaced bars arranged in pairs, pivoted at their bottom ends to the lateral edges of said base, a brace bar detachably connecting the upright bars on one lateral edge of said base together, a frame pivoted to the top ends of said spaced bars, a perforated plate carried by said frame, a movable jaw capable of a vertical movement carried 120

105

115

125

130

by said frame above said plate, a treadle pivoted to one pair of said bars, means operatively connecting said treadle with said movable jaw for imparting a downward movement to said movable jaw toward said perforated plate when said treadle is depressed, and means for returning said movable jaw and treadle to their normal position upon release of said treadle.

10 3. A mop wringer comprising a rectangular base having upright flanges at its lateral edges, upright, spaced standards arranged in pairs, pivoted at their bottom ends to said base flanges, a brace bar detachably connecting the said standards pivoted on the same upright flanges together, a frame pivoted to the top ends of said upright standards, a horizontally disposed, perforated plate fixed to said frame, standards 20 rising from the sides of said perforated plate frame, a shaft journaled in said standards, a movable jaw pivoted on said shaft, a treadle pivoted to one pair of said standards, means operatively connecting said 25 treadle with the said movable jaw for imparting a downward, swinging movement to said movable jaw toward said plate when said treadle is depressed, and means for returning said movable jaw and treadle to 30 their normal position upon the release of said treadle.

4. A mop wringer comprising a rectangular base having upright flanges at its lateral edges, upright, spaced standards arranged in pairs pivoted at their bottom 35

edges to said upright flanges, a brace bar detachably connecting the upright standards pivoted on the said upright flanges, a frame pivoted to the top ends of same upright standards, a perforated plate secured 40 in said frame, standards rising from the sides of said frame, a shaft journaled in said standards, bars pivoted on said shaft, a movable jaw fixed to the front ends of said bars, and a transverse shaft extending through 45 said bars adjacent said movable jaw, a treadle pivoted to one pair of said bars, links operatively connecting said treadle with said last mentioned shaft for imparting a downward movement to the movable jaw toward 50 said plate when said treadle is depressed, a lever pivoted on the first mentioned shaft journaled in said standards, said lever extending at its front end into the vicinity of and operatively engaging with said second 55 mentioned shaft, the rear end of said lever extending into the plane of the rearmost of the upright standards, and a contractile, coiled spring operatively connecting the rear end of said lever to the fixed part of said 60 standards.

In testimony that I claim the foregoing as my invention I affix my signature in the presence of two witnesses, this 30th day of January A. D. 1917.

THEODORE W. HANRATH.
